ADDING MACHINE

John Cuccio, Westport, and Reginald R. Gallant, Bristol,
Conn., assignors to Underwood Corporation, New
York, N.Y., a corporation of Delaware

Filed Oct. 15, 1963, Ser. No. 76,990

Term of patent 14 years

(Cl. D64—11)

FIG. 1

FIG. 2

FIG. 3

Fig.4

FIGURE 1 is a front perspective view of an adding machine showing our new design;

FIGURE 2 is a rear perspective view thereof;

FIGURE 3 is a right side elevational view; and

FIGURE 4 is a front elevational view thereof.

The dominant features of the design are shown in full lines; the broken line showing of the paper being for illustrative purposes only.

We claim:

The ornamental design for an adding machine, as shown and described.
